CLAIM

The ornamental design for a combined mobile phone and pen with retractable display, as shown and described.

DESCRIPTION

FIG. 1 is a perspective view of a combined mobile phone and pen with retractable display showing our design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view of the combined mobile phone and pen with retractable display in a first state of use for reference; and,

FIG. 9 is a perspective view of the combined mobile phone and pen with retractable display in a second state of use for reference.

1 Claim, 9 Drawing Sheets
